(57) **CLAIM**

We claim the ornamental design for a beach table, as shown and described.

DESCRIPTION

FIG. 1 is a perspective view of the beach table of the present invention.

FIG. 2 is a front side view thereof.

FIG. 3 is a rear side view thereof.

FIG. 4 is a right side view thereof.

FIG. 5 is a left side view thereof.

FIG. 6 is a top plan view thereof; and,

FIG. 7 is a bottom plan view thereof.

In the drawings, the broken lines illustrate environment and form no part of the claimed design.
